UNITED STATES PATENT OFFICE.

JOHN P. ODGERS, OF PHILADELPHIA, PENNSYLVANIA, ASSIGNOR TO THE
A. M. COLLINS MANUFACTURING COMPANY, OF SAME PLACE.

DESIGN FOR A CARD-MOUNT.

SPECIFICATION forming part of Design No. 31,954, dated December 5, 1899.

Application filed November 9, 1899. Serial No. 736,428. Term of patent 7 years.

To all whom it may concern:

Be it known that I, JOHN P. ODGERS, a citizen of the United States, residing in Philadelphia, Pennsylvania, have invented a certain 5 new and original Design for a Card-Mount, of which the following is a specification.

My design is fully shown in the accompanying drawing; and it consists, essentially, of a border composed of a succession of tulip-like 10 figures, the continuity of this border being interrupted at top and bottom by figures of substantially triangular form and each composed of a succession of scrolls.

In the drawing, 1 represents the tulip-like 15 figures of the border, and 2 the triangular

scroll-formed figures at the top and bottom of the same.

Having thus described my invention, I claim and desire to secure by Letters Patent—

The design for a card-mount, substantially as herein described and as shown in the accompanying drawing.

In testimony whereof I have signed my name to this specification in the presence of 25 two subscribing witnesses.

JOHN P. ODGERS.
